CLAIM

The ornamental design for a pot-lid holder, as shown and described.

DESCRIPTION

FIG. 1 is a front side perspective view of a pot-lid holder showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is another front side perspective view thereof, shown in an environmental use, shown in reduced scale; and,

FIG. 9 is another front perspective view thereof, shown in alternate environmental use, shown in reduced scale.

The broken lines of FIGS. 8–9 are included to show unclaimed environmental subject matter that form no part of the claimed design.

1 Claim, 8 Drawing Sheets
